(57) **CLAIM**

The ornamental design for a kitchen utensil holder, as shown and described.

DESCRIPTION

FIG. 1 is an upper front perspective view of a kitchen utensil holder showing my new design;

FIG. 2 is a side elevational view thereof, and wherein all sides thereof have the same appearance;

FIG. 3 is a top view thereof;

FIG. 4 is an upper front perspective view of a kitchen utensil holder showing a modified embodiment of my new design;

FIG. 5 is a side elevational view thereof, and wherein all sides thereof have the same appearance; and,

FIG. 6 is a top view thereof.

The bottom views of both embodiments of the kitchen utensil holder do not form a portion of the ornamental design.
